VOTING MACHINE

Alvin N. Gustavson, Jamestown, N. Y., assignor
to Automatic Voting Machine Corporation,
Jamestown, N. Y., a corporation of Delaware

Substituted for abandoned application Serial No.
188,966, February 5, 1938. This application
September 23, 1939, Serial No. 296,305

3 Claims. (Cl. 235—54)

1

This invention relates to an improvement in voting machines and more particularly to a mechanism for requiring a voter to cast a complete ballot, and is a refile of my abandoned application, Serial No. 188,966, filed February 5, 1938.

In elections for representatives to general assembly, representatives to conventions, or other office groups, there are always more candidates seeking nomination or election than there are offices to be filled. Consequently, some of the candidates must be defeated and others nominated or elected. At elections of this nature the voter is instructed to cast his ballot for the same number of candidates as there are offices to be filled in a given office group. If a few voters individually fail to cast their ballots as instructed, this would have little or no effect on the outcome of an election, but it was found that a group of voters, by rearrangement, could defeat the purposes of the election by casting their ballots for only one candidate instead of a number of candidates equal to the number of offices in the office group. In this manner the particular candidate would receive votes equal to that of the group of voters and the other candidates would receive none. The favored candidate would therefore be the equivalent of two votes ahead of any of the other candidates. To illustrate, let it be assumed that ten candidates are seeking election to five offices and that fifty voters agreed to cast their ballot for one given candidate instead of for five. The favored candidate would thus be the equivalent of one hundred votes ahead of any of the other nine candidates. This practice is not only unethical and contrary to the intention of election laws, but in some cases, where prejudice of one kind or another prevails, it would be possible to assure the election of any given candidate provided a sufficient minority group of voters agreed to cast their ballot in the manner described.

The present invention is directed to the provision of a mechanism for controlling balloting in elections involving candidate groups. The device is directly connected with an entrance or exit mechanism, located on the face of the voting machine and operable by the voter or at the side of the machine and operable by an election official. It is also connected with certain interlocking straps of the voting machine which represent a group of candidates seeking election to a lesser number of offices. A voter must cast his ballot for the same number of candidates of the group up for election as there are offices to be filled and by so doing, the present device operates to release

2

the entrance or exit mechanism whereby an election official or the voter himself may lock the machine preparatory to registering the ballot.

One of the objects of the invention lies in the provision of a mechanism for a voting machine which requires a voter, under certain election conditions, to cast a complete ballot.

Another object of the invention lies in the provision of a mechanism which requires a voter to cast ballots for the same number of candidates as there are offices to be filled in a given candidate group.

Another object of the invention lies in the provision of a mechanism for a voting machine which prevents the voter registering his ballot and leaving the machine until he has cast a complete ballot.

Another object of the invention lies in the provision of a mechanism for a voting machine which prevents the election officer's manipulation of the entrance knob to release a voter until a complete ballot has been cast.

Other and further objects of the invention will be more fully understood from a consideration of the following specification taken in conjunction with the accompanying drawings, and in which

Figure 1 is a rear elevation of one modification of the invention applied to a voting machine;

Figure 2 is an enlarged plan view of the structure shown in Figure 1;

Figure 3 is a vertical longitudinal sectional view, similar to Figure 1, showing another position of certain of the movable parts thereof;

Figure 4 is a vertical sectional view of the mechanism as applied to the main interlocking mechanism of a voting machine, being taken substantially on the line 4—4 of Figure 1;

Figure 5 is an enlarged sectional view of the invention, being taken substantially on the line 5—5 of Figure 3, and

Figure 6 is another enlarged vertical sectional view taken substantially on the line 6—6 of Figure 1.

Reference is now had to the drawing wherein the invention is shown to comprise an auxiliary interlocking mechanism generally indicated by the reference numeral 19. The mechanism includes a pair of plates 11 and 12 which are held in spaced parallel relationship in any suitable manner, as by blocks 13. Projecting through suitable openings in the blocks 13 are rods 14, the lower ends of which terminate in bases 15. A spring 17 encircles the rod 14 and serves to normally extend the rod and base. Secured to the outer face of plate 12 are lugs 18 having

upwardly opening slots or grooves 19. The interlock 10 is secured to the main interlocking mechanism 21 of the voting machine by engaging lugs 18 with one of the plates of said main interlock, the spring-pressed rods 14 and bases 16 serving to prevent disengagement of these lugs (see Figure 4).

The plates 11 and 12 are formed with inwardly directed horizontal channels 22 and 23. These channels cooperate to form a guide-way for one or more plates. In the present instance two plates 24 and 26 are provided since the auxiliary interlocking mechanism shown is adapted to control release of the entrance knob through either or both of two office groups. It is contemplated, however, that the guide-way formed by the channels 22 and 23 may be enlarged or the plates reduced in thickness to adapt the device for controlling as many as five or six office groups. The mechanism may, therefore, be adapted to control as many office groups as will ordinarily be required in any election.

Projecting downwardly from one end of plate 24 is a shaft 27. The end of this shaft projects through an opening in the horizontal flange 28 of a bracket 29, being secured against displacement in any suitable manner as by a cotter pin. The lower end of the bracket 29 may be integral with or joined to one side of a bar 31 which lies within the space defined by the members 11 and 12. The other end of the bar 31 is fitted with a further bracket 32, the horizontal flange 33 of which is provided with an upstanding pin 34 which projects through a block 36. The block 36 is mounted in the guide-way formed by the channels 22 and 23 and is movable longitudinally of the device in a manner hereinafter set forth. In order that the bar 31 may normally assume one of its extreme positions, a spring 37 is provided which connects the end of the bar adjacent bracket 32 with a pin 38 on plate 11. Plate 24 is now observed to be movable longitudinally of the guideway by movement of block 36. This plate is provided with two substantially identical openings 39 and 41. Plate 26 may be mounted upon and is movable relative to plate 24. One end of this plate is provided with a downwardly projecting shaft 42 which terminates in a bracket 43. The bracket 43 is integral with or secured to one end of a bar 44. The bar 44, located between plates 11 and 12, is provided with a further bracket 46 from which projects a shaft 47. A block 48, similar to the block 36, is mounted to be movable in the channels 22 and 23 and is joined to one end of rod 47. A spring 49 connects the bar 44 with plate 12 and causes the bar to normally assume the same extreme position as bar 31. Plate 26 is provided with openings 51 and 52 which coincide with openings 39 and 41 when the machine is locked.

A bracket 53 is secured to the outer face and adjacent one end of plate 12. The upper portion 54 of this bracket projects above the plate 12 and is curved inwardly to partly overlie the ends of plates 24 and 26. A suitable opening in the portion 54 supports pin 56 on which is mounted an arm 57. A shaft 58 is pivotally joined to one end of the arm 57. The shaft 58 projects downwardly through an opening in the flange 59 of a further bracket 61. The end of the arm 57, remote from shaft 58, is pivotally connected with a strap 62 which, as shown in Figure 1 of the drawing, is directed upwardly of the side wall of the voting machine and sup-

ported by a pin 63. The pin 63 is mounted on a strap 64 which extends upwardly of the machine and connects with the mechanism adapted to lock or unlock the curtain control lever. The lower end of the strap 64 is mounted on a pin 66 which terminates the inner end of an entrance knob 67 mounted on one wall of the voting machine. The entrance knob 67 is vertically movable, being shown in Figure 1 of the drawing.

Adjacent each of the blocks 36 and 46 and supported in the channels 22 and 23 are rollers 68 which are laterally movable along the channel and are identical in structure with rollers shown in the main interlock 21. Interlocking straps 69 connect a predetermined group of main interlocking straps 71 with the auxiliary interlock 10. The straps 69 may, as shown in the drawing, be formed in three parts which include a portion 72 joined to the main interlocking strap, a portion 73 and a link 74 pivotally connecting these portions. The lower end of portion 73 projects downwardly between a pair of rollers 68 and terminates in a lug 76. The illustration referred to above of ten candidates seeking nomination or election to five offices is carried out in the drawing and, therefore, eleven rollers provide accommodation for ten auxiliary interlocking straps 69. As shown in Figure 1, the enlarged portions of rollers 68 are in contact with each other being so positioned at one end by a grouping pin 77 and at the other end by the block 36. When an indicator on the face of the voting machine has been moved to voting position, the main interlocking strap 71 therefore is raised, carrying with it the auxiliary interlocking strap 69. As the auxiliary strap 69 is raised the lug 76 thereof is projected upwardly between a pair of rollers causing the rollers to move block 36 laterally a distance equivalent to the thickness of the lug. This block must move inasmuch as the grouping pin 77 is suitably fixed to plates 11 and 12 and cannot be moved. It will, of course, be understood that arrangement is provided to re-locate the grouping pin in the event that more than ten straps 69 are to be utilized.

Having set forth the structural features of the invention, description of the operation thereof is as follows: It is assumed that, among other candidates listed on a voting machine to which the present invention is applied, there are ten candidates up for election or nomination and that there are only five offices available. The voter moves the conventional indicators on the face of the voting machine for one candidate in the group and the corresponding main interlocking strap 71 is thereby raised. Inasmuch as there is an auxiliary interlocking strap 69 connected with each main interlocking strap in this group, said auxiliary strap will also be raised. This movement of the auxiliary interlocking strap laterally displaces one or more rollers 68 and causes block 36 to move along the channels 22 and 23. Block 36 is connected through rod 31 with plate 24 and the opening 39 in plate 24 is thus moved out of registry with shaft 58. As four more main and auxiliary interlocking straps 71 and 69 are actuated, the rollers will have been laterally moved from the position shown in Figure 1 to that of Figure 3 and block 36, through bar 31, will have caused plate 24 to assume a position whereby opening 41 registers with shaft 58. To illustrate the fact that the invention adapts a voting machine to more than one group, a substantial duplicate of the set-up of the structure has been pro-

vided and includes block 48, bar 44 and plate 26. It is assumed the voter has also selected five of the ten candidates in this group, moved the indicators to voting position and caused the laterally movable rollers to move block 47 along the channels 23 and 22. This movement, through bar 44, has caused plate 26 to move along the channels. Opening 51 has moved out of registry with shaft 58 and opening 52 into registry therewith. The voter now indicates to the election official that he has completed his ballot and said official raises the entrance knob 61. This movement raises strap 64 and releases the curtain control lever whereby the voter may leave the booth. It also raises strap 62 which causes arm 57 to pivot about pin 56 and shaft 52 to project downwardly through the concentric openings 52 and 41 of plates 26 and 24.

The above description assumed that the voter had cast a proper ballot. If a voter failed to indicate his preference for a candidate of each of the five offices and only caused four straps 71 and 63 to be raised, blocks 36 and 48 would have caused plates 24 or 26 to move an insufficient distance along the channels 22 and 23 to bring openings 41 or 52 to alignment with the shaft 58. Thus, if the voter indicated that he was ready to leave the booth and the election official started to raise the entrance knob 61, shaft 58 would strike the upper surface of one or the other of plates 24 and 26. It would, therefore, be impossible for the entrance knob to be raised and the mechanism connected with strap 64 actuated to release the voter. The election official would therefore immediately be apprised of the fact that the voter had not cast a complete ballot and he would so inform the voter and the error would be corrected.

It is to be understood that the present invention is applicable to a conventional voting machine and, in duplicate arrangement, beyond that shown in the drawing, may adapt said machine to require proper voting in any number of office groups. Furthermore, the election official will know immediately upon his manipulation of the entrance knob whether or not a voter has cast his ballot in the prescribed manner.

Although applicant has shown and described only one modification of an auxiliary interlocking mechanism connected with and adapted to control operation of the voting machine entrance knob in group voting, it will be understood by those skilled in the art that other modifications or adaptations of the structure may be made without departing from the spirit and scope of the invention as set forth in the hereunto annexed claims.

Having thus set forth my invention what I claim as new and for which I desire protection by Letters Patent is:

- 5 1. In a voting machine having an entrance and exit control member and a plurality of indicator operated interlocking straps, a mechanism for controlling operation of said member comprising an auxiliary interlock, laterally movable rollers in said interlock, auxiliary interlocking straps separating said rollers and being joined to certain of said indicator operated straps, a perforated plate in said auxiliary interlock connected with and adapted to be moved as said rollers are moved, means connected with and operable by said member to enter one of said perforations when said plate is moved to occupy a predetermined position with respect to said means.
- 10 15 2. In a voting machine having an entrance and exit control member and a plurality of indicator operated interlocking straps, a mechanism for controlling operation of said member comprising an auxiliary interlock, laterally movable rollers in said interlock, auxiliary interlocking straps separating said rollers and being joined to certain of said indicator operated straps, a laterally movable plate in said auxiliary interlock connected with and adapted to move as said rollers are moved, said plate having spaced openings therein, an arm joined to said member and having a shaft adapted to project into one or the other of said openings when said plate occupies either of two positions, whereby to permit operation of said member.
- 20 25 30 35 40 45 3. In a voting machine having an entrance and exit control member, a mechanism for controlling operation of said member comprising an auxiliary interlock, including laterally movable rollers, a block adapted to be moved by said rollers, a plate in said auxiliary interlock having openings, a bar connecting said plate with said block, an arm joined to said member, a shaft on said arm, said shaft being movable by said member to register with one of the openings in said plate when said rollers have been actuated to move said plate a given distance.
